REFRIGERATING APPARATUS

Earnest J. Dillman, Detroit, Mich., assignor to
 Detroit Lubricator Company, Detroit, Mich., a
 corporation of Michigan

Application April 9, 1937, Serial No. 135,959

33 Claims. (Cl. 62—5)

My invention relates generally to refrigerating apparatus and more particularly to refrigerating apparatus of the generator-absorber type.

5 One of the objects of my invention is to provide a generator-absorber type of refrigerating apparatus in which the temperature of the evaporator is positively controlled to maintain the temperature thereof at a desired, substantially 10 constant temperature irrespective of changes in the heat load.

Another object of my invention is to provide a new and improved generator-absorber type of refrigerating apparatus which is efficient in operation, maintains a substantially constant evaporator temperature irrespective of the heat load, and one in which auxiliary means for aiding in the conduction of heat away from the refrigerant condenser is eliminated without sacrificing 20 efficiency of operation of the system.

Another object of my invention is to provide a generator-absorber type of refrigerating system controlled in a manner such that irrespective of the heat load of the condenser of the system, 25 the burner of the system will be extinguished or heat supplied thereby decreased when substantially all of the refrigerant in the generator-absorber has been evaporated, so as to provide an efficient system and one which will be economical to operate.

Another object of my invention is to provide a refrigerating system of the above mentioned character in which the evaporator of the system is maintained at a desired low, substantially constant 35 temperature and in which a generating cycle will not be started until substantially all of the refrigerant medium in the evaporator has returned to the generator-absorber so as to provide an efficient system.

40 Another object of my invention is to automatically control the temperature of the evaporator of a generator-absorber refrigerating apparatus in an efficient but inexpensive manner.

Another object of my invention is to provide 45 a new and improved control for controlling the temperature of the evaporator of a generator-absorber type of refrigerating apparatus.

Another object of my invention is to provide 50 a new and improved control of the above mentioned character responsive to the temperature of both the evaporator and the generator-absorber to control the refrigerating system in an efficient manner.

The invention consists in the improved construction and combination of parts, to be more

fully described hereinafter and the novelty of which will be particularly pointed out and distinctly claimed.

In the accompanying drawings, to be taken as a part of this specification, I have fully and clearly illustrated my invention, in which drawings—

5 Figure 1 is a diagrammatic view of a generator-absorber refrigerating system embodying my invention;

Fig. 2 is a view shown partly in elevation and partly in section of a control device for the system of Fig. 1 and embodying features of my invention;

Fig. 3 is a view of my control device with the cover removed to show the operating parts there- 15 of;

Fig. 4 is a top plan view shown partly in elevation and partly in section of the control device, and taken along the line 4—4 of Fig. 3;

Fig. 5 is a view shown in section of certain 20 structural details of the control device and taken along the line 5—5 of Fig. 4;

Fig. 6 is a view shown in section of the control device and taken along the line 6—6 of Fig. 2; 25

Fig. 7 is a view in side elevation of a part of the device of Fig. 2 and looking from right to left thereof;

Fig. 8 is a view shown in section of structural 30 details of the control device and taken along the line 8—8 of Fig. 7, and

Fig. 9 is a view showing a modified form of my generator-absorber unit.

Referring now to the drawings by characters of reference and first to Fig. 1, the refrigerating system shown comprises in general a generator-absorber unit or apparatus 1, a refrigerant evaporator 2, a refrigerant receiver 3 and a refrigerant condenser 4. Any suitable refrigerant medium may be employed such as, for example, a 40 solution of ammonia and water. The generator-absorber 1 may be of any suitable type and may include a refrigerant container or tank 6 beneath which an oil burner 7 may be provided for heating the refrigerant in the tank or container 6. The container 6 is preferably provided with one or more vents 6^a for the escape to outside atmosphere of the products of combustion. A supply conduit, generally designated 8, communicatively connects the container 6 above the 45 level of the solution therein with the receiver 3. From the container 6 the supply conduit 8 preferably has an upwardly extending conduit portion 9 in series with a heat transfer member such as a rectifier or absorbent condenser 10. 50 55

The rectifier or condenser 10 serves to cool the aqueous vapor, enroute to the receiver 3 in the conduit portion 9, to a temperature such that most of the water vapor which, as is well known, condenses at a higher temperature than ammonia, is condensed and returned by gravity, via conduit portion 9, to the container 6. The conduit 8 has a vertically extending conduit portion 11 connected to the refrigerant receiver 3. The conduit portion 11 has the condenser 4 interrelated therein. At the condenser 4 the temperature of the gaseous ammonia is lowered to a condensing temperature to liquefy the refrigerant, and from the condenser 4 the liquid ammonia is delivered to the refrigerant receiver 3.

The refrigerant evaporator or heat exchanger 2 may be of any suitable type and may be disposed in an enclosed space to be cooled, such as a compartment of a heat insulated box or refrigerator cabinet (not shown). The evaporator 2 may have a header 13 communicatively connected to the receiver 3 by a supply conduit 14, which conduit preferably opens into the header 13 through the top wall thereof, or thereinto at a point above the level of the liquid ammonia refrigerant in the header. The header 13 is preferably encased in heat insulating material 13a. A check valve 15 is provided in the horizontal portion 15a of the conduit 8 that connects the vertical conduit portions 9 and 11 leading respectively to the generator-absorber container 6 and the receiver 3. This check valve prevents back flow or return of refrigerant medium to the generator-absorber from the receiver 3 with the result that a pressure is maintained in the receiver, which pressure will cause the liquid refrigerant to flow from the receiver 3 up through the supply conduit 14 into the evaporator header 13 during the absorption cycle of the refrigerating system when the pressure is reduced in the generator-absorber container 6. Communicatively connecting the conduit 4 and the conduit portion 15a on the inlet side of valve 16, there is preferably a vertically extending conduit 16 for the purpose of equalizing the pressure in the system during the generating cycle, and in this conduit 16 there is provided a check valve 17 for preventing flow of refrigerant from conduit 14 to conduit 8 via conduit 16 during flow of refrigerant from receiver 3 to evaporator 2. Communicatively connecting the header 13 and the generator-absorber container 6 below the liquid level therein there is a conduit 18 through which the refrigerant vapor returns to the generator-absorber from the evaporator header during the absorption cycle of the system, and preferably this conduit 18 is connected into the header 13 through the top wall thereof or above the liquid ammonia refrigerant therein. The vapor return conduit 18 preferably extends downward from the evaporator 2, along one side of the generator-absorber container 6 to a point adjacent the bottom thereof and is then bent and has an upwardly extending end portion 19, the end of which may be secured in and to the side wall of container 6 at a point below the level L-L of the aqueous solution therein, the level L-L indicating a desired lowest level that the aqueous solution will reach during the generating cycle of the system.

In the present instance, the evaporator 2 has a plurality of depending U-shaped conduits 20 connected into the underside of the header 13, only one of the conduits being shown, these

conduits providing extended heat transfer or cooling surfaces and also providing or defining a compartment below header 13 for receiving one or more ice trays (not shown). The end of one leg of each of the U-shaped conduits 20 terminates at its upper end in and is secured in and to the bottom wall of the header 13 while each of the other conduit ends or legs preferably projects upwardly, as at 21, through an aperture in the bottom wall of and into the header, 10 to a point above the highest attained level of the liquid ammonia refrigerant therein. Beneath and externally of the header 13, each of the upstanding conduit portions or legs, designated 21a, which terminate in the portions 21 has a 15 surrounding wall or conduit 22 spaced from the conduit portions 21a to provide an annular evaporating chamber for receiving the liquid ammonia refrigerant. The conduits 22 have upper open ends secured in and to the bottom wall of 20 the evaporator header 13, and have their lower ends closed and sealed around legs 21a, as at 24. Depending from the header 13 there is preferably provided a water sump 25 the lower end of which may be disposed below the U-shaped 26 conduits 20 and the upper end of which may project upwardly within the header 13 to a point adjacent the top thereof and above the highest attained liquid level. Communicatively connecting each of the conduit portion 21a and 30 the water sump 25, externally of and below the header 13, there is a horizontally extending conduit 26 for the passage of water from each of the conduit portions 21a to the water sump 25. Extending downwardly within the water sump 35 25 to a point adjacent the bottom thereof, as at 26a, there is one end of a water return conduit 27, the other end of which is preferably secured in and to the bottom wall of the generator-absorber container 6, as at 27a.

A conduit 30 has one end 31 communicatively connected to the generator-absorber container 6 and its other end communicatively connected to the upstanding conduit portion 19 of the vapor return conduit 18. The end 31 of the 45 conduit 30 is preferably secured in and to a side wall of container 6 at a point slightly above the point of connection of the vapor return conduit portion 19. The other end of conduit 30 is preferably connected to the vapor return 50 conduit portion 19 slightly above the bend or lowermost point of conduit 18. The conduit 30, conduit 19 and container 6 provide a circulatory system for aqueous refrigerant medium which circulates therethrough so that after the burner 55 is extinguished, or during the absorption cycle of the system there is circulation for a purpose to be hereafter described in detail. The conduit 30 has a horizontally disposed loop portion 32, and secured to and in thermal contact with 60 the legs of portion 32 there is preferably a plurality of spaced plates or fins 33 providing extended cooling surfaces for enhancing the conduction of heat away from the conduit loop portion 32. Enclosing the loop portion 32 there 65 is a casing or housing 34 of heat insulating material having a top wall 34a provided with an opening 35, therethrough that is preferably controlled by a light weight or substantially frictionless damper 36. The bottom of the housing 70 34 may be open, as shown, for the entrance of air thereinto, and the rate at which the air is permitted to escape through the opening 35 to outside atmosphere, by the damper 36, determines the rate of cooling of the aqueous solu- 75

tion in the generator-absorber container 6 and determines the corresponding rate of evaporation of the refrigerant in the evaporator 2.

My control device, designated in general by the numeral 37, controls operation of the burner 7 in accordance with the level of the aqueous solution in the generator-absorber 1 unless the temperature of the solution should increase beyond the predetermined temperature at which the control is set, in which event the burner would be shut off. The control device 37 also operates the damper 36 in accordance with the temperature of the evaporator 2 to maintain the temperature of the evaporator substantially constant irrespective of change of heat load. The control device 37 may include a gravity feed fuel control having a casing 38 containing a chamber 39, see Fig. 2, in which fuel such as oil may be maintained at a substantially constant level by a float 40 operating a valve 41 controlling a fuel inlet port 42. The inlet port 42 may be connected by a supply conduit 43 to a reservoir tank (not shown) or to any other suitable source of fuel supply, and in the supply conduit 43 there is preferably provided a manually operable valve 43^a for starting and stopping flow of fuel to the chamber 39. The constant level chamber 39 has an outlet 44, and connecting this outlet and the burner 7 there is provided a conduit 45 through which oil may flow by gravity from chamber 39 to the oil burner 7.

Integral with the bottom wall of and disposed within chamber 39, there is preferably an upstanding tubular wall member 47 that overlies and communicates with the outlet 44. Adjacent the bottom wall of casing 38 the tubular member 47 preferably has a reduced bore portion 48 providing an internal, upwardly facing port and seat 49. Positioned for vertical reciprocal movement in the tubular member 47, above port 49, there is a valve member 50 preferably having at its lower end a conical face 51 for cooperating with port 49 to control flow therethrough, and consequently control flow of fuel to the burner 7. In the side wall of the tubular member 47 there is preferably provided a slot 52 through which oil may flow from the constant level chamber 39 into the tubular member 47 for flow through port 49 when the valve 50 is open or raised from its seat. When the valve 50 is seated, as shown in Fig. 2, flow of oil to the burner 7 will be discontinued and the burner will, of course, be extinguished. In order to light the burner 7 automatically, a constantly burning pilot burner 53 may be provided and located adjacent the main burner 7. The pilot burner 53 may be connected to a suitable source of fuel supply by means of a conduit 53^a in which there is preferably provided a manually operable valve 53^b for opening and closing the conduit to flow therethrough. The valve member 50 has a stem 54 that extends upwardly within the constant level chamber 39 and projects through the top wall thereof, the said top wall being formed, in the present instance, by a removable cover 55. The cover 55 has an aperture 56 therethrough for slidably receiving and guiding the valve stem 54, and preferably the cover 55 has an upstanding tubular boss 57 externally of the casing 38 and surrounding the valve stem 54 in spaced relation thereto. A helical coil spring 58, Fig. 2, surrounds the valve stem 54, within the chamber 39, and has one end abutting the underside of the casing cover 55 and its other end abutting an external annular flange 59 of the valve

stem 54. The spring 58 is under compression acting to move the valve 50 down onto its seat to close the port 49 to flow therethrough to stop flow of fuel to the burner 7.

Mounted on the cover 55 and removable therewith as a unitary structure there is an actuating mechanism for actuating the valve 50 and for actuating the damper 36. The actuating mechanism has a casing 60 preferably of rectangular shape having a top wall 61, bottom wall 62, side 10 walls 63, 64 and end walls 65, 65^a. In the present instance, the side wall 64 and the end walls 65, 65^a are integral and are removable from the casing as a cover. Screws 66 may extend through apertures in the side wall 64 and thread into the opposite side wall 63 to hold the cover in place. In the bottom wall 62 of the casing 60 there is provided an aperture through which the upstanding tubular boss 57 of the casing cover 55 projects upwardly within casing 60 slightly above the casing bottom wall 62. Disposed within the casing 60 there is a metallic supporting member 68 having a base 69 seating on the casing bottom wall 62, the base 69 having an aperture therethrough for receiving the upstanding tubular boss 57 of casing cover 55. The tubular boss 57 is externally threaded for receiving a nut 70 by means of which the cover 55, casing 60 and supporting member 68 may be rigidly secured together.

The supporting member base 69 is preferably rectangular in shape and extends longitudinally of the casing 60, the base having upturned, substantially parallel flanges 71, 72 that extend substantially parallel with the casing side walls 63, 64. Journaled for rotation in aligning apertures in the flanges 71, 72 there is a shaft 73, and surrounding the shaft 73 and extending between the flanges 71, 72 there is preferably a tubular member 74 that may be secured to the shaft for rotation therewith by a pin 74^a, see Fig. 5. The tubular member 74 preferably has a substantially horizontally extending enlarged end portion or shank 75 disposed adjacent the inner side of the upstanding flange 72, the enlarged portion 75 providing a vertical abutment face or shoulder 16 that faces inwardly or toward the flange 71. Preferably the enlarged portion or shank 75 is of rectangular form and extends longitudinally of the casing 60, and this enlarged portion constitutes a lever by means of which the tubular member 74 and shaft 73 may be rotated. Carried by the rotatable tubular member 74 there is a lever 77 that is to rotate with the tubular member to actuate the valve 50. The lever 77 may have an aperture therethrough adjacent one end for receiving the member 74, and may be positioned against the shoulder 16 of member 74 as shown. At the shoulder 16 the tubular member 74 may have an enlarged portion 76^a which may be polysided, and the aperture in the lever 77 in which the said polysided portion positions may be of like shape so as to prevent relative movement between the tubular member 74 and the lever 77, or these parts may be connected for rotation together in any other suitable manner. The lever 77 extends longitudinally of the casing 60 toward the end wall 65 thereof, and the free end of the lever preferably has a laterally and substantially horizontally extending flange 78 that overlies the upper end of the valve stem 54. Preferably a screw 79 is adjustably screw threaded into the upper end of the valve stem 54, longitudinally thereof, and extends above the upper end of the valve stem and is received in an aperture provided

in the lever flange 78. The screw 79 may have a head 80 positioned above the upper surface of the lever flange 78, and below the screw head 80 the screw 79 may have a portion of reduced diameter 5 to provide opposed horizontal abutment surfaces 82, 83 for abutment with opposite sides of the lever 77. The opposed abutment surfaces 82, 83 are suitably spaced from each other so that on opening of the valve 50 the lever 77 will have a 10 desired, predetermined pivotal movement, or lost motion, before the lever 77 will engage the upper abutment surface 82 and raise the valve 50 from its seat.

Supported by the upturned supporting member 15 flanges 71, 72 there are movable arms or levers 84, each flange having one lever, these levers extending substantially parallel with each other toward the casing end well 65, and longitudinally of and on opposite sides of the lever 77. Preferably the levers 84 are attached to the flanges 71, 72 by resilient hinge members 85 in a manner such that the levers are movable toward and away from each other in planes substantially transverse to the plane of movement of the lever 77 about 20 its fulcrum. Rigidly secured to the lever 77 there is an upwardly extending abutment member 86 seating on the upper surface of the lever flange 78 adjacent the free end of the lever 77 and between the free ends of levers 84. The abutment member 86 has recesses in opposite sides thereof providing sockets 87 that face one toward each of the levers 84 which also have inwardly facing recesses providing sockets 88 adjacent their free ends. Connecting the lever 77 and the levers 84 25 there is a pair of movable thrust members or pins 89 that preferably have their opposite ends pointed for seating in the sockets 87, 88. A helical coil spring 90 is preferably provided for urging the levers 84 toward each other, and in so doing 30 acts through the levers and the thrust pins 89 to pivot lever 77 in a counterclockwise direction, as seen in Fig. 3. When the valve 50 is seated, as shown in Fig. 2, the thrust pins 89 will be in alignment, or on so-called dead center, but when the lever 77 is pivoted slightly in a counterclockwise 35 direction to lift the abutment member 86, as seen in Fig. 3, the pins 89 will be moved out of alignment permitting the spring 90 to pivot lever 77 with a snap action.

50 Mounted on the casing top wall 61 there is a temperature responsive power element or actuator, designated in general by the numeral 91, that acts through the lever 77 to actuate the valve 50 in response to increase of temperature 55 of the generator-absorber container 6. The power element 91 may include a casing 92 that is preferably mounted on the top wall of casing 60, externally thereof. The lower end of the power element casing 92 is open and preferably 60 has an external rectangular flange 93 for seating on the casing top wall 61. The casing flange 93 may be provided with apertures at its corner portions for receiving screws 94 for rigidly securing the casings 92 and 60 together. A supporting member 95 in the form of a plate is secured and hermetically sealed to the inner side 65 wall of casing 92 adjacent the lower or open end thereof. The supporting plate 95 extends transverse to the side wall of the casing 92 and is provided with a centrally disposed aperture therethrough. Disposed in the power element casing 92 there is a metallic bellows 96 that cooperates with the casing 92 to provide an expansible chamber 97, and one end of the bellows 96 is 70 secured and hermetically sealed to a border por-

tion of the supporting plate 95 around the aperture therethrough. The other or free upper end of the bellows 96 is secured and hermetically sealed to a movable end wall or plate 97^a that is disposed toward the power element casing top 5 wall, which top wall serves as a stop for limiting expansion movement of the bellows 96. The power element 91 includes a bulb element 98 that is preferably disposed within the generator-absorber container 6, and communicatively connecting the bulb element 98 and the expansible chamber 97 there is a conduit or tube 100. The power element may be charged with any suitable temperature responsive, expansible-contractible fluid, such as for example butyl-alcohol. Preferably the bulb element 98 is enclosed or surrounded by a closed well or conduit 100^a, preferably formed of metal and arranged in contact or in good heat transfer relation with the bulb element 98. The well of conduit 100^a 20 preferably projects into the container 6 through a side wall thereof, and the conduit preferably extends horizontally and rests on or is arranged in good heat transfer relation with the crown sheet or top wall 100^b of the combustion chamber 25 for the burner 7.

Carried by the bellows movable end wall 97^a there is a rod-like thrust member 101 that transmits compression movement of the bellows 96 to the lever 77. The thrust rod 101 extends centrally through the bellows 96 into the casing 60 through an aperture in the top wall 61 thereof, and adjacent its lower end the thrust rod is preferably received and guided in an aperture provided in a horizontally disposed flange portion 102 projecting from the supporting member vertical side flange 72. The flange portion 102 overlies the lever 77 and serves as a stop for engagement by the upper edge portion 102^a of the lever to limit pivotal movement thereof in a clockwise direction, as seen in Fig. 6. At its lower end the thrust rod 101 is preferably pointed, as at 103, for seating in an upwardly facing recess or socket 104 provided in the enlarged portion or lever 75 of the rotatable tubular member 74 to which the lever 77 is connected. The thrust member 101 is arranged to engage the enlarged portion 75 at one side of the longitudinal axis of shaft 73 such that downward movement of the thrust member will rotate member 75 and lever 77 in a counterclockwise direction, as seen in Fig. 6, which will result in the valve 50 being moved to closed position. At its free end the lever 77 has a downwardly directed, extended portion 105, the lower end of which is adapted 50 to engage the upper surface of the supporting member base 69 to limit pivotal movement of the lever 77 in a counterclockwise direction, as seen in Fig. 6.

Surrounding the thrust rod 101 there is preferably a helical coil spring 106 having one end, or its upper end abutting the bellows movable end wall 97^a and its other, or lower end abutting a supporting member 107 that may be a U-shaped bracket. The U-shaped bracket 107 may 65 be rigidly secured to and depend from the casing top wall 61, within the casing, and may have a horizontally disposed portion 108 above flange 102, provided with an aperture through which the thrust rod 101 may extend. The spring 106 70 is under compression exerting a force opposing closing of the valve 50 by the power element 91, and the force exerted by this spring determines the temperature to which the generator-absorber bulb element 98 must be heated be- 75

fore the power element will act to extinguish the burner 7.

The tubular member 74 that rotates with the shaft 73 preferably has an externally threaded 5 end portion for receiving an internally threaded tubular member or sleeve 110 that rotates with the tubular member. A plate-like lever member 111 is supported by the shaft 73 and is provided with an aperture adjacent one end 10 thereof for receiving the tubular member 110, the lever 111 extending toward the casing end wall 65, or in a direction opposite from the direction in which the lever 77 extends from shaft 73. A slip clutch 112 is provided and is adapted 15 to couple lever 111 to the tubular member 74 when the lever 111 is pivoted in a counterclockwise or valve opening direction, as seen in Fig. 3, and the slip clutch may include a pair of friction discs 113 that may be formed of rubber or 20 other material having a suitable coefficient of friction. The friction discs 113 surround, or have centrally disposed apertures for receiving the tubular member 110, and are positioned one 25 on each side of and preferably have flat surfaces in abutment or engagement with opposite sides of the lever 111.

Preferably the friction discs 113 are each provided with cup-shaped metallic retainers, one for each disc and designated respectively 114 and 30 115, of which the retainer 115 preferably has a circular shaped aperture for receiving the tubular member 74 and is preferably positioned flat against the lever 77. The retainer 115 is tightly and frictionally held against the lever 77, for rotation therewith, by the tubular member 110 which has one end abutting the retainer 115 urging the retainer against the lever 77. The tubular member 110 preferably has a square shank 116, and threaded onto the tubular member 74 40 there is preferably a lock nut 117 that abuts the end of the shank 116 and prevents movement of the tubular member 110 relative to the tubular member 74. The retainer 114 surrounds the square shank 116 of member 110 and is provided 45 with a centrally disposed rectangular aperture for receiving the shank so that the retainer 114 will rotate with the shaft 73. Preferably a helical coil spring 118 surrounds the shank 116 of member 110 and has one end abutting the lock nut 117 and the other end abutting the retainer 114, which retainer is adapted to move longitudinally 50 of the tubular member 110. The spring 118 is under compression and urges the opposed faces of the friction discs 113 against the opposite sides 55 of the lever 111 to couple the lever to the shaft 73. In this construction the lever 111 is operable to exert a predetermined torque through the friction disks to the shaft 73 and will slip relative to the shaft by means of the friction disks 113 60 when that torque is exceeded. When the lever 77 is pivoted in either direction, the clutch 112 will slip, due to the relatively great force necessary to move the power element, to be hereinafter described, so that pivotal movement of the lever 65 77 will not be transmitted to the lever 111. Also, if lever 111 is pivoted in a clockwise direction, as seen in Fig. 3, the clutch 112 will slip to prevent movement of lever 77, due to the relatively great component of force exerted by the spring 70 90 urging the lever 77 in a counterclockwise direction, but when the lever 111 is pivoted in a counterclockwise direction, the valve 50 being in closed position, the clutch will couple lever 111 to the shaft 73 so that lever 77 will be pivoted to 75 open the valve 50 because the thrust pins 88 are

substantially in their dead center position so that the spring 90 exerts substantially no component of force on the lever 77 opposing rotation by the lever 111. Preferably the shaft 73 has an end portion projecting externally of the casing 5 through an aperture in the casing side wall 63, and secured to the shaft externally of the casing 60 there is a manually operable lever 120 by means of which the lever 77 may be pivoted to open and close the valve 50. 10

The lever 111 is actuated by a temperature responsive actuator or power element, designated in general by the numeral 122, that is responsive to the temperature of the evaporator 2, or to the temperature of the ammonia refrigerant 15 therein. The power element 122 may be and preferably is constructed in the same manner as the hereinbefore described power element 91, and therefore a detailed description of the power element 122 is deemed to be unnecessary. Preferably the power element 122 is larger than the power element 91, or is constructed so that it will exert a greater force than the power element 91. The power element 122 comprises in general a casing or container 123, a bulb element 124 connected by a tube or conduit 125. Secured to and disposed within the casing 123 there is a metallic bellows 126 that cooperates with the casing to provide therewithin an expansible pressure chamber 127 that is communicatively connected to the bulb element 124 by the conduit 125. The power element 122 may be charged with any suitable temperature responsive, expansible-contractible fluid, for example iso-butane. Preferably the power element bulb 124 projects into the evaporator 2 and is disposed above the liquid level therein so that the bulb will be subjected to the temperature of the vaporous ammonia therein. The power element casing 123 may be mounted on the upper surface of the top wall 61 of casing 60, alongside of the smaller power element 91, and preferably substantially overlying the free end of the lever 111. The bellows 126 has a movable end wall 128, and carried thereby there is preferably a thrust rod 129 for transmitting movement of the bellows 126 to the lever 111. The thrust rod 129 extends centrally through the bellows 126 into the casing 60, through an aperture in the top wall 61 thereof, and downwardly within the casing 60, and projects externally of the casing through an aperture in the casing bottom wall 62. Externally of the casing 60 the thrust rod 129 is connected adjacent its lower end to one end of a lever 130 that may be pivotally supported by the heat insulating housing 34, the other end of the lever 130 being pivotally connected to the damper 36 by a link 131. The power element thrust rod 129 is connected to the damper 36 in a manner such that when the thrust rod is moved downward the damper is moved toward open position. Opening of the damper 36 increases air circulation through the housing 34 which increases the rate of cooling of the aqueous solution circulating through the conduit loop 32, and consequently increases the rate of cooling of the aqueous solution in the generator-absorber 1 during the absorption cycle of the system. By controlling the rate of cooling, or rate of absorption of the aqueous solution in the generator-absorber 1 in response to the temperature 70 of the refrigerant or ammonia in the evaporator 2, the temperature of the evaporator may be positively controlled and maintained substantially constant irrespective of change in the heat load. 75

Within the casing 60 the power element thrust

rod 129 has a portion of reduced diameter, as at 131a, providing spaced, opposed, substantially parallel and horizontal shoulders or abutment surfaces 132. Rigidly secured to the lever 111 adjacent its free end there is a laterally extending abutment member, preferably a pin 133 that positions between the abutment shoulders 132 for cooperation therewith to pivot the lever 111. The abutment surfaces 132 are spaced a distance 10 apart such that there will be a predetermined lost motion between the rod 129 and the lever 111 so that the power element 122 can operate the damper 36 within a desired operating range without pivoting lever 111. Surrounding the 15 power element thrust rod 129 within the casing 60 there is preferably an open ended tubular member 134 that may seat on the casing bottom wall 62. The tubular member 134 may be rigidly secured to the casing bottom wall 62 by a second 20 open ended tubular member 135 that may be inserted in member 134 and receive and guide the thrust rod 129. The insert tubular member 135 may have external annular flanges 136 at its opposite ends, one of which flanges may hold 25 spring fingers, to be hereinafter described, against the upper surface of the member 134 and the other of which may abut the underside of the casing bottom wall 62. A plurality of upturned spring fingers 137 are provided for frictionally 30 engaging the thrust rod 129 to dampen vibration thereof. The spring fingers 137 may be integral and formed out of a piece of spring metal that may have a centrally disposed aperture for receiving the insert member 135, and may seat on 35 the upper end of member 134 and be held thereagainst by the upper flange of insert member 135. At their upper ends the spring fingers 137 are preferably bent or rounded, as at 138, so as to have convex surfaces for engaging the thrust 40 rod 129 to provide a smooth bearing surface on each of the fingers. Surrounding the spring fingers 137 and positioned in the indented or concave portions formed by the bent or rounded upper ends, there is preferably a coil spring 140 45 under tension urging the spring fingers 137 inwardly toward and holding the fingers against the rod 129 to increase the friction on the rod 129. A lower end portion of the rod 129 is preferably of reduced diameter, as at 141, providing 50 a downwardly facing, external annular shoulder 142. Adjacent its lower end the tubular insert member 135 has a bore portion 143 of reduced diameter for receiving the reduced rod portion 141, and providing an upwardly facing internal 55 shoulder 144 for abutment by the rod shoulder 142 to limit downward movement of the thrust rod 129.

Surrounding the thrust rod 129 there is a helical coil spring 145 that has one, or its upper end 60 abutting the bellows movable end wall 128 and its other, or lower end abutting a movably adjustable supporting member 146. By changing the position of or moving the supporting member 146, the magnitude of the spring force may 65 be changed to determine or regulate the temperature at which the power element 122 will overcome spring 145 and open the valve 50. Pivotally supported within the casting 60 there is an adjustment lever 147 that supports the 70 abutment member 146 and through movement of which lever the position of the spring abutment member 146 may be changed to change the force exerted by the spring 145. The casing side wall 63 may be provided with a pair of spaced apertures through which a pair of spaced lugs or 75

flanges 148 may project into the casing 60, and the flanges 148 may have aligned apertures for receiving a shaft 149 for pivotally supporting the adjustment lever 147. The lugs 148 may be formed out of a plate 150 that preferably lies flat against the outer surface of the casing side wall 63. The adjustment lever 147 preferably has a pair of spaced, substantially parallel lever arms 151 between which the movable abutment or supporting member 146 positions, the member 146 preferably being a cup-shaped member having an upper open end provided with an outturned annular flange 152. Adjacent their ends, the lever arms 151 preferably have upwardly directed extended portions 154 that are preferably pointed at their upper ends for engaging in downwardly facing, oppositely disposed recesses or sockets formed in the outturned flange 152 of the adjustable supporting member 146.

Carried by the casing side wall 63 there is a 20 manually operable adjustment mechanism for pivoting the adjustment lever 147 to change the force exerted by the spring 145. The casing side wall 63 is preferably provided with an aperture through which a fitting or tubular member 155 extends into the casing 60, the fitting 155 preferably being internally threaded for adjustably receiving an externally threaded adjustment member 156. The fitting 155 also extends through an aperture provided in the plate 150, out of which 30 the shaft supporting lugs 148 are formed, and extends through an aperture in a dial plate 157. The fitting 155 preferably has a head 158 externally of the casing 60, and the dial plate 157 is disposed between the head 158 and plate 150. An 35 inner end portion of the fitting 155 may be peened over, as shown, to rigidly secure the fitting, plate 150 and dial plate 157 to the casing rear wall 63. The adjustment member 156 has a centrally disposed, longitudinally extending 40 bore 160 that opens through the inner end thereof and this bore slidably receives and guides a thrust member, preferably a pin 161. The opposite ends of the pin 161 are preferably rounded, as shown, and the inner end of the pin engages 45 or abuts a connecting or cross member 162 that is integral with and joins the lever arms 151 of the lever 147, the pin 161 preferably engaging the cross member 162 at a point below the longitudinal axis of the shaft 149 and at a point 50 substantially midway between the lever arms 151. The adjustment member 156 has an enlarged bore portion 163 that opens through its outer end, and the bore 163 is preferably internally threaded for receiving a manually operable adjustment screw 164 for adjusting the position 55 of the abutment pin 161 with respect to the adjustment member 156. A handle 165 for conveniently rotating the member 156 may be secured to the outer end thereof by means of a 60 screw 166 that may be screw threaded into bore 163. The handle 165 may have its outer end pointed, as at 167, Fig. 7, to serve as a pointer for cooperation with indicia (not shown) on the dial plate 157 to aid in accurately setting the 65 device. When the thrust member 155 is rotated in a direction such that it is moved inwardly and pivots adjustment lever 147 in a clockwise direction, facing Fig. 2, then the force exerted by spring 145 will be increased with the result that 70 the power element 122 will open valve 50 at a higher refrigerant temperature.

The operation of the herein described refrigerating system and controls therefor is as follows: To start the system the manually operable valve 75

53^b controlling flow of fuel to the pilot burner 53 is opened, after which the pilot burner may be lighted. The manually operable valve 43^a controlling flow of fuel to the fuel reservoir or constant level chamber 39 is then opened and by means of the manually operable lever 120 the outlet valve 50 may be moved to open position to permit flow of fuel to the main burner 7 which is then ignited by the pilot burner 53. The valve 50 can be moved to open position by the manually operable lever 120 because when the temperature of the aqueous solution in the container 6 is below a predetermined temperature, or at room temperature, the thrust rod 101 of the power element 91 will be in a retracted position out of engagement with the lever 77. The parts of the control device will be in the positions shown at the time of completion of a generating cycle of the system. With the lighting of the main burner 7, the generating cycle of the system begins as the burner heats the aqueous solution in the generator-absorber container 6. Heating of the aqueous solution in the container 6 drives out the ammonia in a vaporous state along with some water vapor and the vapor flows up conduit 9 to the condenser 10 where the major portion of entrained water vapor is condensed and returned by gravity to the container 6, the ammonia vapor and the remaining water vapor continuing to the condenser 4 where it is condensed and from whence it flows down through conduit 11 into the receiver 3. As the vapor flows en route to the condenser 4, some of the vapor will pass the check valve 17 and flow through the conduit 16 into the supply conduit 14 to create a pressure in the evaporator for a purpose to be hereafter described. The power element 91, responsive to the temperature of the generator-absorber 1, is set so that it will not close the valve 50 to extinguish the burner 7 at the temperature to which the aqueous solution is normally heated by the burner. During the generating cycle, as liquid ammonia continues to be delivered to the receiver 3 from the generator 6, the level of the aqueous solution in the generator-absorber container 6 will of course decrease, but so long as the liquid level is at a height such that the liquid wets the bulb well 100^a, the fluid in the bulb will remain at the same temperature as the aqueous solution, with the result that the power element 91 will not act to extinguish the burner 7. However, shortly after the aqueous solution level decreases to a level, as at L—L, below the bulb well 100^a thus exposing a portion of the crown sheet 100^b, the temperature of the bulb and fluid therein will be quickly increased by the heat of the burner flame impinging on the crown sheet. As the temperature of the fluid in the bulb 98 reaches a predetermined temperature, the fluid pressure will have compressed the power element spring 106 and have moved lever 77 against the force of spring 90, pivoting the lever 77 in a counterclockwise direction, facing Fig. 6. Since the resistance of spring 90 decreases upon movement of lever 77, the force of power element 91, which will start lever movement, will complete the movement of the valve 50 with a quick or snap action to closed position. When the lever 77 is pivoted as above mentioned, the slip clutch 112 will slip due to the resistance of power element 122 so that pivotal movement of the lever 77 will not be transmitted through the lever 111. Pivotal movement of lever 77 in a counterclockwise direction will permit the valve 50 to descend quickly by gravity, aided by the spring 58 which

urges the valve against its seat 49 and closes the outlet port. Closing of the valve 50 will, of course, stop flow of fuel to the burner 7 which will become extinguished. While under normal conditions the burner 7 will not be extinguished until the level of the aqueous solution in the container 6 decreases to approximately the level L—L, it will be seen that the burner will be extinguished when the level of the aqueous solution is above the level L—L if for any reason the aqueous solution should reach the temperature at which the power element 91 is set to operate. As the weak aqueous solution in the container 6 cools, the absorption cycle begins and cooling of the solution is accomplished by decrease in the pressure in container 6 and accompanying decrease in the pressure in the evaporator 2, which causes liquid ammonia refrigerant to flow from the receiver 3 up through the conduit 14 into the evaporator 2.

20

When all of the liquid ammonia in the receiver 3 has been delivered to the evaporator 2, the evaporator will be substantially filled. The cooling of the evaporator now begins, the liquid ammonia in the evaporator 2 evaporating and cooling or lowering the temperature of the evaporator and thereby the space or compartment in which the evaporator may be located. As the liquid ammonia evaporates in the evaporator 2, the ammonia gas or vapor returns to the generator-absorber 1 via the conduit 18 and is absorbed by the water in conduit member 19 and flows to the generator-absorber where it is diluted by the liquid in the generator container 6. During the absorption cycle of the refrigerating system the weaker aqueous solution in the generator-absorber 1 circulates by gravity through the conduit loop portion 32 due to the radiating effects of the conduit loop portion 32 resulting in a temperature differential between the portion 32 and the generator-absorber container 6. Circulation of the aqueous solution is enhanced or aided by chemically generated heat evolved when the returning, almost pure ammonia vapor dissolves in the weak aqueous solution at the connection of the loop portion 32 and the upstanding vapor return conduit portion 19. The conduit portion 32, and therefore the aqueous solution circulating therethrough, is cooled by air which enters the housing 34 through the bottom thereof, the rate of cooling being determined by the rate of air flow over radiating portion 32 under control of the damper 36. The rate of absorption by the water of the ammonia vapor returning to the generator-absorber 1, and therefore the rate of evaporation of the liquid ammonia in, or the rate of cooling of the evaporator, depend upon the rate at which heat is conducted away from the conduit loop portion 32 in the housing 34.

60

Before the absorption cycle starts, the evaporator header portion 13 will be warm with the result that the bellows 126 of the power element 122 will be compressed by the expandible-contractible fluid of the power element. When the bellows 126 is thus compressed, the thrust or connecting rod 129 will be held in its down position against its stop 144, and the damper 36 will be held in an open position such as will permit a desired, rapid absorption of the ammonia vapor by the aqueous solution in the evaporator 2. As the evaporator 2 cools, the expandible-contractible fluid in bulb 124 of the power element 122 will correspondingly contract permitting the spring 145 to compress the bellows 75

126 which will move the connecting rod 129 upward. Upward movement of the connecting rod 129 will pivot lever 130 in a clockwise direction, as seen in Fig. 1, and will move the damper 36 toward closed position. Movement of the damper 36 toward closed position will restrict the air circulation over the conduit portion 32 thereby decreasing its radiation and the rate of absorption, by the aqueous solution from the container 6 of the returning vapor in conduit 18, with accompanying decrease in the rate of evaporation of the ammonia in the evaporator 2 as the evaporator approaches the desired temperature. Upon predetermined upward movement 15 of the bellows thrust rod 129 the lower or upwardly facing abutment surface 132 thereof will engage the lever pin 133, and predetermined further upward movement of the thrust rod 129 will move lever 111 to its up position preparatory to movement of lever 111 downward to start a generating cycle. The aqueous solution in the generator-absorber 1 will also cool, causing the bellows 96 of the power element 91 to contract under force of the spring 106 and to 20 move the thrust rod 101 upward out of engagement with the abutment member or lever 75 of lever 77 so that lever 77 can be moved upward without opposition for starting a generating cycle. When the evaporator 2 has been cooled to a predetermined desired temperature, determined by the force exerted by the power element spring 145, the power element 122 will have operated the damper 36 to full closed position at which 30 normal heat leakages at the evaporator and from casing 34 will be substantially balanced so as to maintain the desired evaporator temperature substantially constant. For example, if for any reason the heat load on the evaporator 2 is increased, the power element 122 will accordingly move the damper 36 in an opening direction and increase the rate of evaporation of the ammonia refrigerant in the evaporator 2 to thereby compensate for the increase in heat load. Or in other words, for all changes of the heat load 40 on the evaporator 2, the position of the damper 36 will be accordingly and automatically changed or throttled by the power element 122 to correspondingly change the rate of evaporation of the ammonia refrigerant in the evaporator and thereby maintain the evaporator temperature substantially constant. Below a predetermined evaporator temperature after lever 111 has been reset as above noted, the power element 122 will actuate the damper 36 without acting on the lever 111, because of the lost motion connection 50 therebetween provided by the spaced abutment shoulders 132 of the rod 129 and the pin 133 of lever 111. As the quantity of ammonia refrigerant in the evaporator 2 decreases, the damper 36 is correspondingly moved toward open position to increase the rate of evaporation of the ammonia to thereby maintain the evaporator temperature substantially constant. When substantially all of the ammonia in the evaporator 60 2 has been used, or has evaporated, the temperature of the evaporator, and consequently the temperature of the power element bulb 124, will increase which will cause the power element thrust rod 129 to be moved downward. After the thrust rod 129 has been moved downward a predetermined distance its downwardly facing abutment shoulder 132 will engage the abutment pin 133 of lever 111, and continued downward movement of the thrust rod will pivot lever 111 70 in a clockwise direction, facing Fig. 6. When

the power element 122, on heating up of the evaporator 2, pivots lever 111 in a clockwise direction, facing Fig. 6, the friction slip clutch 112 will hold or couple the lever 111 to the shaft 13 with the result that the lever 77 will be pivoted in a clockwise direction. Slight pivotal movement of the lever 77 in a clockwise direction, facing Fig. 6, will move the thrust pins 89 from their dead center positions which will permit the spring 90, acting through the hinge members 88 and pins 89, to pivot the lever with a snap action. After predetermined initial pivotal movement of the lever 77 by the spring 90 the under surface 82 of the valve screw head 80 will be engaged by the lever 77 which will then carry the valve 50 upward away from its seat 49 with a snap action. The lost motion connection between the lever 77 and the valve 50 is provided so that the lever will be in motion before it takes up the additional load of lifting the valve 50. The valve 50 is now open and fuel will again flow to the main burner 7 which will be automatically lighted by the constantly burning pilot light 53 to again start the generating cycle. 25

From the above description it will now be seen that the power element 91 permits the burner 7 to heat the solution in the container 6 until a predetermined substantially constant quantity of the ammonia has been driven off, after which 30 the power element 91 will extinguish the burner. It will also be seen that the other power element 122 permits the burner 7 to remain extinguished until substantially all of the ammonia refrigerant has been used in cooling and maintaining 35 the evaporator cool. Element 122 also actuates the damper 36 to obtain a given temperature in the evaporator by a proper or desired rate of evaporation of the ammonia in the evaporator which is obtained by controlling the rate of absorption of the gaseous ammonia by the water in the container 6. This results in an efficient system since substantially all of the ammonia is utilized each cycle thereby maintaining the evaporator at maximum capacity due to its flooded 40 condition, and the rate at which the refrigerant is absorbed is controlled in accordance with the desired temperature of the evaporator to maintain the evaporator at a desired, substantially constant temperature during the absorption part 45 of the cycle. 50

As is well known, the capacity of a condenser depends upon the difference in temperature between the fluid to be cooled and the cooling fluid which is the temperature differential of the condenser. For this reason the condenser 4 has more capacity in winter with a given generator temperature than in summer because the differential temperature is less with the result that the ammonia will be more quickly driven out of the aqueous solution in winter than in summer. However, as soon as the level of the solution decreases to the level L-L, then the bulb 98 will not be cooled by the surrounding liquid and will be heated by the burner via the metallic container with the result that the bulb will be quickly heated to the temperature at which the power element 91 extinguishes the burner. By this arrangement it will be seen that the burner 7 will not remain lighted any longer than necessary to 60 drive out substantially all of the ammonia from the aqueous solution regardless of the liquid temperature, which of course provides for economical operation of the burner. In the summer time when the condenser has less capacity the burner 65 70

- will remain lighted for a correspondingly longer period in order for the ammonia to be driven from the liquid in the generator or until the temperature of the aqueous solution reaches the predetermined temperature at which the power element acts to extinguish the burner, or until the liquid level in container 6 decreases below the bulb 98. Thus it will be appreciated that the operating temperature of the power element 91 need not be reset or changed for condensers of different capacities, nor need it be reset upon the occurrence of seasonal changes affecting the capacity of the condenser in order to have a predetermined minimum quantity of ammonia remain in the liquid in the generator which insures an ample supply of liquid ammonia to the evaporator every cycle. This is of course advantageous.
- The rectifier or condenser 10 will not remove all of the water from the ammonia vapor with the result that after completion of an absorption cycle of the system there will be some water left in the evaporator 2 which was carried there in solution by the liquid ammonia through conduit 14 and by the ammonia vapor through conduit 16. However, the water-ammonia solution rich in water left in the evaporator at the end of each absorption cycle is returned to the generator-absorber 1 each succeeding absorption cycle in the following manner: When liquid ammonia is again supplied to the evaporator 2, the ammonia will by its own weight push the solution rich in water through the evaporator conduit 20, 21a up to and through the conduit 26 into the water sump 25. During the succeeding generating cycle the pressure of the ammonia vapor transmitted to the evaporator 2, via conduit 16, will act through passageway 26 on the water in sump 25 to force it upward and through conduit 27 to the generator-absorber container 6.
- Referring now to Fig. 9 of the drawings, in this view there is shown a refrigerating system that is similar to the system of Fig. 1 and therefore like parts of the two systems are designated by like numerals. The system of Fig. 9 differs from that of Fig. 1 in the construction of the generator-absorber in that the container 6 is substantially entirely enclosed by heat insulating material 168 instead of having a housed conduit portion for circulation of the aqueous solution as in the system of Fig. 1. In the insulation 168 below the container 6, there is provided an opening 169 for the entrance of air which may flow out through the vents 6a to conduct heat away from the container 6 thereby to cool the aqueous solution therein. A damper 170 controls flow of air through the opening 169 to control cooling of the aqueous solution, and is actuated by the power element 122 in accordance with the temperature of the evaporator and thereby maintains the evaporator temperature substantially constant. The system shown in Fig. 9 operates in the same manner as the hereinbefore described system shown in Fig. 1.
- What I claim and desire to secure by Letters Patent of the United States is:
1. Refrigerating apparatus comprising a generator-absorber for a liquid solution including a refrigerant medium, a refrigerant evaporator communicatively connected to said generator-absorber so that refrigerant may pass therebetween, the level of the liquid solution in said generator-absorber rising and falling in accordance with the quantity of the refrigerant medium in said generator-absorber, means for heating the solution in said generator-absorber to vaporize the refrigerant medium and thereby lower the level of the liquid solution to a predetermined low level, means for condensing the vaporous refrigerant medium for supply to said evaporator, normally acting temperature responsive means directly heated by said heating means and operable at a predetermined temperature for decreasing the heat input by said heating means to the solution, said responsive means being so positioned and arranged relative to the solution level that said responsive means is cooled by the solution to a temperature below said predetermined temperature solely at solution levels above said predetermined low level, said responsive means being operable upon decrease of the solution level to said predetermined low level to be heated by said responsive means to said predetermined temperature, thereby to insure the reduction of solution level to said predetermined level prior to decrease of the heat input by said heating means to the solution, control means operable for controlling the rate of cooling of the solution to control the rate of absorption by the solution in the generator-absorber of the refrigerant evaporating in said evaporator, and means responsive to the temperature of said evaporator to actuate said control means to maintain the evaporator at a desired substantially constant temperature.
  2. Refrigerating apparatus comprising a generator-absorber for a liquid solution including a refrigerant medium, a refrigerant evaporator communicatively connected to said generator-absorber, means for heating the solution in said generator-absorber to vaporize the refrigerant medium, means for condensing the vaporous refrigerant medium for supply to said evaporator, temperature responsive means heated by said heating means and operable at a predetermined temperature to decrease the heat input by said heating means to the solution to initiate an absorption cycle, control means operable to control the rate of cooling of the solution and the corresponding rate of absorption by the solution in said generator-absorber of the refrigerant medium evaporating in said evaporator, and means responsive to the temperature of the evaporator for actuating said control means to maintain the temperature of the evaporator substantially constant, said last-named means also being operable on predetermined increase in the temperature of said evaporator to increase the heat input by said heating means to the solution to initiate a generating cycle.
  3. Refrigerating apparatus comprising, a container for a liquid solution including a refrigerant medium, a refrigerant evaporator, supply and return conduits connecting said container and said evaporator, means for heating the solution in said container to vaporize the refrigerant medium, means for condensing the vaporized refrigerant medium for supply to the evaporator, control means operable for controlling said heating means, means responsive to the temperature of the solution for actuating said control means, said responsive means being operable at a predetermined temperature to decrease the heat input by said heating means to the solution to initiate an absorption cycle, control means for controlling the rate of absorption by the solution in said container of the evaporating refrigerant medium in said evaporator, means responsive to the temperature of said evaporator for actuating said second-named control means to maintain a predetermined substantially constant evaporator temperature, said

- last-named responsive means having a lost-motion connection with said first-named controlling means and operable upon predetermined increase in the evaporator temperature for actuating said first-named controlling means to increase the heat input by said heating means to the solution to initiate a generating cycle.
4. Refrigerating apparatus comprising a heat insulated container for a liquid solution including a refrigerant medium and including insulated top and bottom walls, a refrigerant evaporator communicatively connected to said container, means for heating the solution in said container to evaporate the refrigerant medium, means for condensing the vaporous refrigerant medium for supply to said evaporator, temperature responsive means heated by said heating means and operable at a predetermined temperature to decrease the heat input by said heating means to the solution to initiate an absorption cycle, said top wall being ported for flow of egress air, said bottom wall having an opening through its insulation for the entrance of air to cool the solution and for outflow through said top wall, a damper controlling said opening to control the rate of cooling of the solution and thereby control the rate of absorption by the solution of the refrigerant medium returning from said evaporator to said container, and temperature responsive means responsive to the temperature of the evaporator to actuate said damper to maintain said evaporator at a predetermined substantially constant temperature, said last-named means being operable upon a predetermined increase in temperature to actuate said heating means.
5. Refrigerating apparatus comprising a metallic container for a liquid solution including a refrigerant medium, a horizontally extending conduit system having its ends communicatively connected to said container at different levels below the minimum level of said solution in said container so that gravity circulation of said solution will occur, a refrigerant evaporator communicatively connected to said container, means for heating the solution in said container to vaporize the refrigerant medium, means for condensing the vaporous refrigerant medium for supply to said evaporator, temperature responsive means heated by said heating means and operable at a predetermined temperature for decreasing the heat input of said heating means to the solution, heat insulating material enclosing at least a portion of said conduit system and having an opening therethrough for air to conduct heat away from the portion of said solution in said system, a damper for said opening and operable to control the rate of heat conduction away from said solution portion whereby to control the rate of absorption by said solution of the refrigerant medium in the evaporator, and means responsive to the temperature of said evaporator to actuate said damper to maintain a predetermined desired evaporator temperature.
6. Refrigerating apparatus comprising a metallic container for a liquid solution including a refrigerant medium, a refrigerant evaporator communicatively connected to said container, means for heating the solution in said container to vaporize the refrigerant medium, means for condensing the vaporous refrigerant medium for supply to said evaporator, control means for said heating means, an actuator for actuating said control means to decrease the heat input of said

heating means to the solution, said actuator including a temperature responsive element disposed in the solution in said container and in good heat conductive relation with said container, said actuator being operable when the solution reaches a predetermined high temperature and also being operable when the liquid level of the solution decreases to a level such that said responsive element responds to the relatively higher temperature of said container above said level, means for controlling the rate of absorption by the solution of the refrigerant medium in the evaporator to thereby control the rate of evaporation of the refrigerant medium, and means responsive to the temperature of the evaporator for actuating said last-named controlling means to maintain a desired evaporator temperature, said last-named responsive means also being operable on predetermined increase in the temperature of said evaporator to increase the heat input of said heating means to the solution.

7. Refrigerating apparatus comprising a generator-absorber for a refrigerant medium and including a liquid absorbing solution, means for heating the refrigerant medium and the solution in the generator-absorber to drive off the medium until the solution level in the generator-absorber is reduced to a predetermined level, a refrigerant evaporator, a supply of conduit connecting said evaporator and said generator-absorber, a refrigerant return conduit connecting said evaporator and said generator-absorber, means operable for controlling said heating means, means directly heated by said heating means for normally actuating said controlling means said directly heated means being so positioned relative to said predetermined level that prior to the reduction of the solution level to said predetermined level said heated means is cooled by the solution and subsequent to the reduction of level to said predetermined level the solution is ineffective to cool said heated means, and means responsive to the temperature of said evaporator for actuating said controlling means.

8. Refrigerating apparatus comprising a generator-absorber for a refrigerant medium, means for heating the refrigerant in said generator-absorber, a refrigerant evaporator, a refrigerant supply conduit connecting said generator-absorber and said evaporator, a refrigerant return conduit connecting said generator-absorber and said evaporator, means operable for controlling said heating means, means responsive to the temperature of said generator-absorber for actuating said controlling means, means responsive to the temperature of said evaporator for actuating said controlling means, and means operable for controlling the rate of evaporation of the refrigerant in said evaporator and actuated by one of said actuating means.

9. Refrigerating apparatus comprising a generator-absorber for a refrigerant medium, a refrigerant evaporator, supply and return conduits operatively connecting said evaporator and said generator-absorber, conduit means communicatively connected to said generator-absorber and cooperating therewith to provide a circulatory system for the circulation of the refrigerant medium during the absorbing cycle, a housing enclosing a portion of said last-named conduit means and having an opening for the entrance of air to cool the refrigerant medium circulating through said portion, a damper controlling said opening and operable to regulate the rate of

cooling of the refrigerant medium circulating through said conduit portion, means for heating the refrigerant medium in said generator-absorber, means for controlling said heating means, 5 means responsive to the temperature of said generator-absorber for actuating said controlling means, means responsive to the temperature of said evaporator for actuating said controlling means, said damper being actuated by one of said 10 temperature responsive means.

10. Refrigerating apparatus comprising a generator-absorber for a refrigerant medium, a condenser, a refrigerant evaporator, conduit means connecting said generator-absorber and said condenser, conduit means connecting said condenser and said evaporator, return conduit means connecting said evaporator and said generator-absorber, heating means for said generator-absorber to heat the refrigerant medium, control 15 means for controlling said heating means, means responsive to the temperature of said generator-absorber for actuating said control means, means responsive to the temperature of said evaporator for actuating said control means, conduit means 20 connected to said generator-absorber and to said return conduit means and cooperating with said generator-absorber and a portion of said last-named conduit means to provide a closed system for circulation of the refrigerant medium in the 25 generator-absorber during the absorbing cycle, the refrigerant medium circulating through said circulatory system being cooled by air, means for controlling the rate of cooling of the refrigerant medium circulating through said circulatory system and actuated by one of said responsive means. 30

11. Refrigerating apparatus comprising a generator-absorber for a liquid solution including a refrigerant medium, a refrigerant evaporator communicatively connected to said generator-absorber, means including heating means for separating the refrigerant medium from the solution for delivery to said evaporator, means including a temperature responsive element for controlling said heating means, said temperature responsive element being submerged in the liquid solution when the level of the liquid in said generator-absorber is above a predetermined level, said controlling means being operable to control said heating means to reduce the heat input to the 45 solution in the generator-absorber when the level of the solution decreases to a predetermined level below said temperature responsive means. 50

12. Refrigerating apparatus comprising a generator-absorber for a liquid solution including a refrigerant medium, a refrigerant evaporator communicatively connected to said generator-absorber, means including heating means for separating the refrigerant medium from the solution for delivery to said evaporator, means including a temperature responsive element for controlling said heating means, said temperature responsive element being submerged in the liquid solution when the level of the liquid in said generator-absorber is above a predetermined level, said controlling means being operable to control said heating means to reduce the heat input to the solution in the generator-absorber when the level of the solution decreases to a predetermined level below said temperature responsive means, means cooperable with said generator-absorber to provide a circulatory system for the solution in said generator-absorber, means responsive to the temperature of said evaporator for controlling said heating means and operable 70 to control the rate of heat conduction away from 75

the liquid circulating through said circulatory system to control the rate of absorption of the refrigerant medium by the solution to maintain a substantially constant evaporator temperature.

13. Refrigerating apparatus comprising a generator-absorber for a liquid solution including a refrigerant medium, a refrigerant evaporator communicatively connected to said generator-absorber, means including heating means for separating the refrigerant medium from the solution for delivery to said evaporator, means including a temperature responsive element for controlling said heating means, said temperature responsive element being submerged in the liquid solution when the level of the liquid in said generator-absorber is above a predetermined level, said controlling means being operable to control said heating means to reduce the heat input to the solution in the generator-absorber when the level of the solution decreases to a predetermined level below said temperature responsive means, conduit means cooperable with said generator-absorber to provide a circulatory system for the liquid solution in said generator-absorber, a housing enclosing a portion of said conduit means and having an opening for the entrance of air to conduct heat away from said conduit portion, a damper controlling said opening to control the rate of heat conduction away from said conduit portion, and means responsive to the temperature of said evaporator for regulating the position of said damper. 20 25 30

14. In a control device, a controlling means, a lever operatively connected to said controlling means, a power element operable to pivot said lever to move said controlling means in one direction, a second power element operable to pivot said lever to move said controlling means in an opposite direction, a slip clutch operatively connecting said second-named power element and said controlling means, and manually operable means for actuating said controlling means. 35

15. In a control device, a supporting means, a controlling means, a second controlling means, a lever pivotally supported by said supporting means and operatively connected to said first-named controlling means, a power element operable to pivot said lever to move said first-named controlling means in one direction, a second lever pivotally supported by said supporting means and operatively connected to said second-named controlling means, a power element operatively connected to and for actuating said second-named lever and operatively connected to and for actuating said second-named controlling means, and a slip clutch operatively connecting said first-named lever and said second-named lever, said second-named power element being operable to actuate said first-named lever through said slip clutch to move said first-named controlling means in the opposite direction. 40 45 50 55 60

16. In a control device, a supporting means, a controlling means, a second controlling means, a lever pivotally supported by said supporting means and operatively connected to said first-named controlling means, a power element operable to pivot said lever to move said first-named controlling means in one direction, a second lever pivotally supported by said supporting means and operatively connected to said second-named controlling means, a power element operatively connected to and for actuating said second-named lever and operatively connected to for actuating said second-named controlling means, and a slip clutch operatively connecting said first-named 65 70 75

- lever and said second-named lever, said second-named power element being operable to actuate said first-named lever through said slip clutch to move said first-named controlling means in the opposite direction, said second-named power element and said second-named lever having a lost-motion connection therebetween.
17. In a control device, a supporting means, a controlling means, a second controlling means, 5 a lever pivotally supported by said supporting means and operatively connected to said first-named controlling means, a power element operable to pivot said lever to move said first-named controlling means in one direction, a second lever pivotally supported by said supporting means and 10 operatively connected to said second-named controlling means, a power element operatively connected to and for actuating said second-named lever and operatively connected to for actuating said second-named controlling means, a slip clutch operatively connecting said first-named lever and said second-named lever, said second-named power element being operable to 15 actuate said first-named lever through said slip clutch to move said first-named controlling means in the opposite direction, said second-named power element and said second-named lever having a lost-motion connection therebetween, and snap acting mechanism for transmitting movement of said first-named lever to said first-named controlling means.
18. In a control device, the combination with a movable controlling means and a pair of power elements for actuating the controlling means, of 20 a slip clutch for operatively connecting one of said power elements to the controlling means and of a rigid mechanical connection for the other of said power elements to the controlling means.
19. In a refrigerating system of the absorption type, a container for a liquid solution including a refrigerant medium, heating means for heating the solution to vaporize the refrigerant medium, and a control device for normally controlling said heating means, said control device including a 25 temperature responsive element arranged to be heated by said heating means, said control device having a first and a second position and being operable to move from said first to said second position when said element is heated to a predetermined temperature to decrease the heat input by the heating means to the solution said device being operable upon decrease in temperature below said predetermined temperature to automatically move to said first position, said element being arranged in heat transfer relation 30 with and maintained by the solution at a temperature below said predetermined temperature when the level of the solution is above a predetermined normal level, said element being heated to a temperature above the temperature of the solution by said heating means when the level of the solution is below said predetermined level.
20. A refrigerating apparatus comprising a generator-absorber, a condenser and an evaporator communicatively connected in operative relation, means to heat said generator-absorber, means for controlling flow in heat exchange relation to said generator-absorber of a heat abstracting medium, means controlling the heat supplied by said heating means, means controlling said flow-controlling means, means operable upon occurrence of a predetermined low liquid level in said generator-absorber to actuate said heat controlling means to decrease the heat supply, means responsive to the temperature of said evaporator 35 and acting through said last-named means to actuate said heat controlling means to increase the heat supply, means operatively connecting said temperature responsive means to said flow-controlling means to regulate cooling of said generator-absorber, and lost-motion means operatively connecting said temperature responsive means to said heat controlling means so that said temperature responsive means will be ineffective to actuate said heat controlling means to decrease the supply of heat to said generator-absorber.
21. A refrigerating apparatus comprising a generator-absorber, a condenser and an evaporator communicatively connected in operative relation, means to heat said generator-absorber, 40 means for controlling flow in heat exchange relation to said generator-absorber of a heat abstracting medium, means controlling the heat supplied by said heating means, means controlling said flow-controlling means, means responsive to predetermined decrease of refrigerant medium in said generator-absorber, a lever operatively connecting said responsive means to said heat controlling means, means responsive to the temperature of said evaporator, a lever operable by said evaporator responsive means, clutch means interconnecting said levers and being operable to transmit movement to said heat controlling means upon increase of evaporator temperature, and means operatively connecting said temperature responsive means to said flow controlling means.
22. A refrigerating apparatus comprising a generator-absorber, a condenser and an evaporator communicatively connected in operative relation, means to heat said generator-absorber, 45 means for controlling flow in heat exchange relation to said generator-absorber of a heat abstracting medium, means controlling the heat supplied by said heating means, means controlling said flow-controlling means, means responsive to predetermined decrease of refrigerant medium in said generator-absorber, an operating shaft, a lever carried by said shaft and operatively connecting said responsive means to said heat controlling means, means responsive to the temperature of said evaporator, a second lever carried by said shaft and operatively connected to said temperature responsive means, means to transmit movement from said second lever to said first-named lever, and means operatively connecting said temperature responsive means to said flow controlling means.
23. A control device comprising a conduit having a valve port, a longitudinally reciprocal valve member controlling said port, an operating arm, means supporting said arm for pivotal movement, means on said valve member in the path of movement of and spaced from said arm, means operable to move said arm with a quick action to cause engagement of said arm and said valve member means so that said valve member will be actuated subsequent to initial movement of said arm and with a quick movement, and means for initiating movement of said last-named means.
24. A control device comprising a supporting member having a top wall with an aperture and having a bottom wall and opposed side wall portions, a shaft extending between and supported by said side wall portions, an operating arm on said shaft, a reciprocal member engageable and movable by said arm, a second arm on said shaft, means to couple said arms for movement in unison, a thrust member extending through said aperture and cooperable with and operable to

move said first-named arm to move said reciprocal member in one direction, and a thrust member engageable with said second-named arm and operable through said first-named arm to move 5 said reciprocal member in the opposite direction.

25. A control device comprising a supporting member having a top wall with an aperture and having a bottom wall and opposed side wall portions, a shaft extending between and supported 10 by said side wall portions, an operating arm on said shaft, a reciprocal member engageable and movable by said arm, a second arm on said shaft, means to couple said arms for movement in unison, a thrust member extending through said 15 aperture and cooperable with and operable to move said first-named arm to move said reciprocal member in one direction, a thrust member engageable with said second-named arm and operable through said first-named arm to move said reciprocal member in the opposite direction, a 20 laterally movable member extending with said first-named arm and from one of said portions, a force-transmitting member positioned between said laterally movable member and said first-named arm, and means urging said laterally movable member toward said force-transmitting member so that said last-named means will act 25 to move said reciprocal member upon movement of said reciprocal member by said last-named thrust member.

26. In a control device, an actuated means, a pair of actuating means, friction clutch means operatively connecting said actuated means to one of said actuating means for movement in one 30 direction and operable to render said one actuating means ineffective to move said actuated means in another direction, and means operatively connecting the other of said actuating means to said actuated means for moving said actuated 35 means in said other direction.

27. A control device for liquid fuel burners, comprising a casing having a liquid reservoir with an inlet and an outlet for intercalation in the burner fuel supply line, a reciprocal metering 40 valve controlling flow from said outlet, resilient means having a force urging said valve toward closed position, lever means cooperable with said valve and operable to oppose the force of said resilient means, spring means acting on said 45 lever means and opposing operation of said valve by said resilient means, said spring means having a component of force acting on said lever means, said component changing in force upon movement of said lever means to release the force of said resilient means, temperature responsive 50 means, a lever operable by said responsive means, clutch means operable to transmit movement from said lever under the force of said responsive means to said lever means, movement of said 55 lever means by said lever acting to release the force of said spring means thereby to overcome said resilient means and open said valve, means responsive to temperature created by the burner, and means operable to transmit movement from 60 said last-named responsive means to said lever means to move said lever means in opposition to the force of said spring means so that said resilient means can move said valve toward closed 65 position.

28. In a device of the character described, conduit means, valve means operable upon movement to control flow of fluid through said means, temperature sensitive means, lever means operatively connected to said valve means, a lever 70 member operatively connected to said sensitive

means for movement thereby, said lever member being operable upon movement in one direction to move said lever means in one direction so that said valve means is moved, means operable upon movement of said lever member in a second direction to render said lever member ineffective to move said lever means, and means for moving said lever means in a direction opposite to said lever means one direction. 5

29. In a device of the character described, conduit means, valve means operable upon movement to control flow of fluid through said means, lever means operatively connected to said valve means, a lever member, temperature sensitive means operatively connected to said lever member and operable upon increasing temperature to act through said lever member to move said lever means in one direction so that said valve means is moved, means operable to render said lever member upon movement in a second direction 20 ineffective to move said lever means, and means for moving said lever means in a direction opposite to said lever means one direction. 10 15

30. In a device of the character described, conduit means, valve means operable upon movement to control flow of fluid through said means, temperature sensitive means, lever means operatively connected to said valve means, snap-acting toggle means operable upon predetermined movement of said lever means so that said valve means 25 is moved with a snap action, a lever member operatively connected to said sensitive means for movement thereby, said lever member being operable upon movement in one direction to move said lever means in one direction so that said 30 valve means is moved with a snap action, means operable upon movement of said lever member in a second direction to render said lever member ineffective to move said lever means, and means for moving said lever means in a direction opposite to said lever means one direction. 35 40

31. In a control device comprising a casing having a liquid containing chamber, said casing having a valve port in a wall of said chamber, a longitudinally reciprocal valve member controlling said port, an operating arm, means rigid with said casing and supporting said arm for pivotal movement, means on said valve member in the path of movement of and spaced from said arm, spring actuated snap-acting means operable to move said arm with a quick action to cause engagement of said arm and said valve member 45 means so that said valve member will be actuated subsequent to initial movement of said arm and with a quick movement, and means for initiating movement of said last-named means. 50 55

32. In a control device, an actuated means, a pair of actuating means, means operatively connecting said actuated means to one of said actuating means for movement in one direction, means operatively connecting the other of said actuating means through said connecting means to said actuated means for moving said actuated means in another direction, said last-named actuating means being ineffective to move said actuated means in said one direction, lost motion means connecting said actuated means and said first-named actuating means so that said connecting means when moving in said other direction will be in motion prior to actuation thereby of said actuated means, and spring actuated toggle means operative so that said actuated means is moved with a snap action in said one direction. 60 65 70

33. A device for controlling flow of fluid fuel to the burner of an absorption refrigerating ap- 75

paratus, comprising a casing having an outlet passageway, a valve member controlling flow through said passageway, a shaft supported on said casing, lever means carried by said shaft and having a portion cooperable with and operable to actuate said valve member, a pair of fluid-charged temperature responsive power elements positioned on the opposite side of said shaft from said passageway and in lateral relation and being operable alternately to actuate said valve

member, a lever on said shaft, a thrust member operatively connecting one of said power elements to said lever, clutch means for transmitting movement from said lever to said lever means, a second lever cooperable with said lever means, a thrust member operatively connecting said second lever to the other of said power elements, and means cooperable with said lever means to impart a quick movement to said valve member. 5
